CLAIM

The ornamental design for the drink bottle, as shown and described.

DESCRIPTION

FIG. 1 is a perspective view of a drink bottle showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof, wherein the drink bottle is separated into a first bottle and a second bottle;

FIG. 9 is a perspective view of the first bottle of the drink bottle, shown separately for completeness of illustration;

FIG. 10 a front elevational view of FIG. 9;

FIG. 11 is a rear elevational of FIG. 9;

FIG. 12 is a left elevational view of FIG. 9;

FIG. 13 is a right elevational view of FIG. 9;

FIG. 14 is a top plan view of FIG. 9;

FIG. 15 is a bottom plan view of FIG. 9;

FIG. 16 is a perspective view of the second bottle of the drink bottle, shown separately for completeness of illustration;

FIG. 17 a front elevational view of FIG. 16;

FIG. 18 is a rear elevational of FIG. 16;

FIG. 19 is a left elevational view of FIG. 16;

FIG. 20 is a right elevational view of FIG. 16;

FIG. 21 is a top plan view of FIG. 16; and,

FIG. 22 is a bottom plan view of FIG. 16.
